COMBINED VARIABLE POWER SUPPLY AND CIRCUIT TESTER DEMONSTRATION UNIT

Joseph Don Jack, 314 Warren St.,
Harrison, N.J. 07029

Filed Mar. 24, 1975, Ser. No. 561,061

Term of patent 7 years

Int. Cl. D19—07

U.S. Cl. D19—62

FIG. 1

FIG. 2

FIG. 3

FIG. 4

FIG. 1 is a front perspective view of a combined variable power supply and circuit tester demonstration unit, showing my new design;

FIG. 2 is a side elevation opposite that shown in FIG. 1;

FIG. 3 is a front perspective view of a second modified embodiment of the form illustrated in FIG. 1; and

FIG. 4 is a perspective view of a third modified embodiment illustrated in FIG. 1.

The undisclosed rear portions of the combined variable power supply and circuit tester demonstration unit are substantially plain and unornamented.

I claim:

The ornamental design for a combined variable power supply and circuit tester demonstration unit, as shown and described.
